GROUP-ADDRESS SYSTEM

Edward Lindley Bowles, Wellesley Farms, Mass.

Application September 28, 1932, Serial No. 635,211

7 Claims. (Cl. 179—1)

The present invention relates to group-address systems, and more particularly those in which: first, the voice of a speaker making an address, music, or other form of sound energy that it is desired to transmit, in amplified form, to an audience or other group, is picked up by one or more microphones; next, the electrical facsimile of the sound input is amplified by the amplifying equipment to which the microphone is electrically connected; and finally, horn loud speakers or other devices project the reproduced sound into or upon the audience.

According to present-day practice, the microphone is usually placed immediately before the speaker, and the loud-speaker horn some distance away; in fact, as far away as is conveniently possible.

To place the microphone near the loud speaker has involved difficulties, for if any appreciable amount of sound energy coming from the loud speaker should reach the microphone, howling effects would be produced, of so objectionable a nature as to render the system practically inoperative. Not only has it been necessary to separate the loud speaker and the microphone, therefore, but it has been considered advisable properly to orient the loud speaker, even when at a distance.

The separating of the microphone and the loud speaker has the advantage that it lends itself well to the covering of large areas, where relatively large energy outputs are desired. A very objectionable artificiality is thus, however, created. The audience observes the speaker on a platform or pulpit, and sees his lips move, but must accustom itself to the sound coming from an entirely different point. There is a consequent constant effort of the audience to reconcile such dissociated sound and vision manifestations, as if one's eyes were set in one place and one's ears in another.

An object of the invention, accordingly, is to provide a novel, group or public-address system that shall overcome this difficulty.

A further object is to provide a novel, group-address system with the use of which a speaker's sound shall appear to come directly from the speaker's lips, thus eliminating the above-described artificiality.

Another object is to provide a novel, group-address system with the use of which a speaker may address his audience without discomfort either to himself or the audience; for, according to the present invention, neither the speaker nor the audience need be aware of the fact that

the speaker's voice, before it reaches the audience, has become supplanted by an amplified facsimile of the same.

As the horns, especially the cluster horns, ordinarily employed in group-address systems, detract from the beauty of the surroundings, particularly in such places as churches, still another object of the invention is to conceal the sound pickup and amplifying or other equipment, so that the audience shall not be conscious of the recreation of the original sound, such as that produced by the speaker's voice.

The invention will now be explained in connection with the accompanying drawings, in which Fig. 1 is a perspective view of a lecture-stand or lectern arrangement embodying the present invention; Fig. 2 is a back elevation of the same, with the back cover removed; Fig. 3 is a side elevation of the same, with the near side removed; Fig. 4 is a vertical section taken upon the line 4—4 of Fig. 2, looking in the direction of the arrows; Fig. 5 is an elevation, partly in section, of a modification; Fig. 6 is a perspective of a further modification, involving a complete, group-address unit on a stage of a theatre or lecture hall; Fig. 7 is a diagrammatic view of circuits and apparatus arranged and constructed in accordance with this invention; and Fig. 8 is a view of a further modification.

The lecture-stand or lectern 1 may be fixed, or it may be portable, so that it may be rolled or otherwise moved from one class room or lecture hall to another of a school or other building. It is provided with a base 2, upon which rests a frame 16, having side walls or panels 4, a front cover wall or panel 11, shown removed in Fig. 2, and a top wall 6. An inner shelf 14, below the top wall 6, separates an intermediately disposed housing 10, above the shelf 14, from a lower housing, for a container or box 5, below the shelf 14. The side walls or panels 4, like the panel 11, may be removable. If the walls or panels of the lectern are made of relatively heavy wood, they will not act as diaphragms, and will not vibrate as a whole, at an objectionable, low frequency. A housing 13 rests on the top wall 6 and is provided with a desk cover board 15 on which may rest a thin, sponge-rubber mat 25, for reducing the noise that may be caused by direct contact of a speaker's papers, watch, and other articles with the wood top of the desk cover board 15.

A transmitter unit 9, comprising a condenser microphone 3 and its associated amplifier, is judiciously arranged in the housing 13, just below

the top thereof. An amplifying unit 7 is disposed in the intermediately disposed housing 10, on the shelf 14. A loud speaker unit 21 is internally housed in the container 5. The loud speaker being thus self contained and acoustically insulated from the surrounding lectern structure, it is possible materially to reduce any sound transmission from the loud speaker system to the lectern body. The loud speaker is provided with a cone 23, neatly covered with a sound-porous cloth or metal netting 8 that, by proper selection, can be made to blend artistically in with the rest of the apparatus to form a neat front panel, rendering the loud speaker 21 inconspicuous to the audience. The microphone opening 12 may be similarly covered, so that not even the speaker shall be aware of its presence.

The condenser transmitter or microphone unit 9 is disposed in acoustic-insulating and resonant-suppressing material 17 that acoustically insulates the microphone 3 from the material of which is made the desk housing 13, comprising the desk cover board 15 and the top wall 6. The material 17 may be felt, packed about the condenser-transmitter unit 9 in two ways: first, beneath the unit, to act as a cushion, substantially to eliminate acoustic conduction from the body structure of the lectern to the transmitter unit 9; and secondly, to fill spaces within the lectern structure, which would otherwise tend to resonate at some sound frequency. The microphone unit 9 is thus acoustically cushioned, and also the objectionable tendency to cavity resonance is overcome.

35 The amplifying unit 7 is treated with sound-insulating and resonance-suppressing material 17 in a manner similar to that described above in connection with the microphone unit 9. The acoustic-insulating, or absorbing and cushioning material 17 is disposed between the amplifier 7 and the shelf 14, and throughout the upper housing 10, so as substantially to eliminate the cavity-resonance.

40 The loud speaker is likewise treated similarly. 45 The box-like container 5 is also lined with any preferred, acoustic-absorbing material, like certain grades of celotex, containing many small holes for the purpose of making the sound absorption more complete. The celotex may, in 50 turn, be covered with felt.

The inside walls of the lectern 1 may likewise be all covered or lined with some material, like felt, to a degree sufficient to eliminate all residual tendency for the lectern walls or panels to 55 resonate as diaphragms. The kinds and quantity of lining material will depend upon the kind of wood used, the thickness, the inside dimensions and the type of the deadening material used.

60 Other sound-absorbing materials may also be used; in combination, not only to prevent the transmission of sound from within the box 5 to the lectern frame 16, but also to absorb the sound radiated from the back of the cone speaker, thus 65 giving it a frequency-response characteristic such as it would have if it were in a baffle, operating into free space on both sides. The presence of the acoustically-absorbing material in the box 5 thus renders it possible to prevent any cavity 70 resonance therein. Such cavity resonance, of course, would have a serious effect on the desired frequency response characteristics of the loud speaker.

75 It thus becomes possible to mount the various parts of the group-address system in a single

lectern 1, very close to the speaker, and where they are completely hidden from view. The speaker's voice is satisfactorily recreated and amplified with relative freedom for acoustic feedback either through the material of which the lectern is constructed, or through the air. The audience is cast under the illusion that the voice it hears comes directly from the speaker's lips.

Where more pronounced directional effects than those obtainable with a cone speaker are desired, 10 or where, for any other reason, it is preferred to do so, a horn speaker, of compact coil or other form, may be employed. If not objectionable in appearance, the directive effect of the cone loud speaker may be increased slightly by means of a 15 short horn 29, as illustrated in Fig. 8. When it is desirable to fix the lectern permanently in position, as in the case of a church pulpit, and if there is sufficient space below the floor, the horn may be relatively long and straight, and 20 extend below the base of the lectern and below the floor, as illustrated in Fig. 5.

It is sometimes convenient to use two microphones 3, instead of only one, as illustrated in Fig. 8. The two microphones may be placed side 25 by side, near the center of the lectern desk housing 13, as in Fig. 2, or one may be placed at each extremity of the desk 13, as shown in Fig. 8.

It is often convenient to have the volume of the sound output from the lectern, group-address 30 system controllable from some remote point. As illustrated in Fig. 6, for example, an individual in the audience may monitor the output of the group-address system from a point 91 at which he is seated. This type of gain in volume control insures a proper coverage of the audience and, at the same time, makes it possible to adjust to that point of amplitude which it simulates the normal amplitude of the speaker's voice. Without such direct control, group-address systems 40 are often adjusted to put out so very much energy that the level is obviously artificial.

The electrical connections may be as diagrammatically illustrated in Fig. 7. The condenser-transmitter unit 9 is illustrated as comprising 45 a condenser transmitter 3, associated with an amplifier 65 and an output transformer 67, all in a shielded case. Other microphone arrangements may also be employed, as is obvious. The microphone unit 9 is connected by means of 50 shielded leads 71, connected to terminals 69 that may be plugged into sockets 73, the shield being grounded at 89, to a remote, volume-control unit, shown as a conventional "T-type", attenuator 77, though any other convenient type of control may be used. This unit is housed in a 55 shielded box 75 and is controlled by a calibrated dial 79. The volume-control unit is connected with an equalizer 35, that may be of any desired type. The equalizer 35 is arranged so that it is 60 possible to adjust the relative proportion of low-frequency and high-frequency energy affecting the power amplifier 7. By means of this equalizer unit, it is possible to compensate for the over-all, frequency-response characteristic of the lectern, group-address unit, when operating in a given environment.

The unit 35 comprises three vacuum-tube amplifiers 45, 47 and 49, associated with an input transformer 51 and an output transformer 53. 70 The tube 45 is coupled to the tube 47 by means of a variable inductor 37 and a variable resistor 39, in series, a by-pass condenser 55 and a conventional, grid-leak potentiometer 57 being also shown. The tube 47 is coupled to the tube 49 by 75

means of a variable condenser 43 and a variable resistor 41, a shunt-feed choke 59 furnishing the B-battery supply to the plate of the tube 47; a by-pass condenser 61 and a conventional, grid-leak potentiometer resistor 57 being also illustrated.

Adjustment of the values of the inductor 37 and the resistor 39 will effect control of the relative amount of amplification of low-frequency energy. The degree of suppression or emphasis is controlled by dials 81, 83. The adjustment of the value of the condenser 43 and the resistor 41 will control the relative amplification of the high, audio-frequency energy. The degree of suppression or emphasis is controlled by dials 85 and 87. With sufficiently high values for the resistors 39 and 41, the unit 35 will have a uniform amplifying effect over the entire band of desired acoustic frequencies.

The resistors 39 and 41, the inductor 37 and the condenser 43 may, of course, be replaced by other shunt elements. In the plate circuit of the tube 47, for example, the condenser 43 may be replaced by a condenser in series with an inductor, variably tunable to series resonance; or, again, such a series-resonance unit may be included in an additional stage of amplification. According to the illustrated embodiment of the invention, however, any adjustments of relative intensity of the different portions of the frequency spectrum may be made on the inductor 37, and the resistor 39, and/or the condenser 43 and the resistor 41 in a mutually exclusive manner. The adjustment of one of these plate-circuit, frequency-control elements does not affect the operation or the adjustment of any other. This, of course, would not be the case if both these elements were connected in the same circuit, and not electrically divorced by means of an interposed, unilateral, vacuum-tube amplifier, such as the amplifier 47.

The monitoring individual may thus have before him the volume-control element 11 and also, if necessary, the equalizer element 35. By locally adjusting the equalizer 35, he may increase the degree of intelligibility of speakers with certain types of voices.

Further modifications will occur to persons skilled in the art, and all such are considered to fall within the spirit and scope of the invention, as defined in the appended claims.

What is claimed is:

1. A group-address system having, in combination, a housing, a loud-speaker in the housing oriented to project sound out of the housing, a microphone outside of the housing at a position such that its sensitive surface is disposed in the acoustical shadow of the loud-speaker but close enough to the loud-speaker so that sound from the loud-speaker would be adapted to travel into the shadow to the microphone in appreciable quantity and thus appreciably actuate the microphone, and acoustic-insulating means positioned in the housing between the loud-speaker and the microphone for preventing the said appreciable actuation of the microphone.

2. A group-address system having, in combination, a housing, a loud-speaker in the housing oriented to project sound out of the housing, a microphone in the housing at a position such that its sensitive surface is disposed in the acoustical shadow of the loud-speaker but close enough to the loud-speaker so that sound from the loud-speaker would be adapted to travel into

the shadow to the microphone in appreciable quantity and thus appreciably actuate the microphone, and acoustic-insulating means positioned in the housing between the loud-speaker and the microphone for preventing the said appreciable actuation of the microphone.

3. A group-address system having, in combination, a housing, a loud-speaker in the housing oriented to project sound out of the housing, a microphone in the housing at a position such that its sensitive surface is disposed in the acoustical shadow of the loud-speaker but close enough to the loud-speaker so that sound from the loud-speaker would be adapted to travel into the shadow to the microphone in appreciable quantity and thus appreciably actuate the microphone, an amplifier in the housing, and acoustic-insulating means positioned in the housing between the loud-speaker and the microphone for preventing the said appreciable actuation of the microphone.

4. A group-address system having, in combination, a lectern comprising a housing having a base and a frame supported by the base having side walls and a top wall, a container in the housing, a loud-speaker in the container oriented to project sound out of the housing, a microphone positioned so that its sensitive surface is disposed in the acoustical shadow of the loud-speaker but close enough to the loud-speaker so that sound from the loud-speaker would be adapted to travel into the shadow to the microphone in appreciable quantity and thus appreciably actuate the microphone, and acoustic-insulating means positioned in the housing between the container and the microphone for preventing the said appreciable actuation of the microphone.

5. A group-address system having, in combination, a lectern having a base, a frame supported by the base having side walls and a top wall, and a shelf below the top wall, whereby a first housing is formed above the shelf and a second housing is formed below the shelf, a container in the second housing, a loud-speaker in the container oriented to project sound out of the housing, an amplifier disposed in the first housing, a microphone positioned so that its sensitive surface is disposed in the acoustical shadow of the loud-speaker but close enough to the loud-speaker so that sound from the loud-speaker would be adapted to travel into the shadow to the microphone in appreciable quantity and thus appreciably actuate the microphone and the amplifier, and acoustic insulating means positioned in the housings between the container, the amplifier and the microphone for preventing the said appreciable actuation of the microphone and the amplifier.

6. A group-address system having, in combination, a lectern having a base, a frame supported by the base having side walls and a top wall, a closed housing disposed on the top wall, a shelf below the top wall, whereby an intermediately disposed housing is formed above the shelf and a lower housing is formed below the shelf, a container in the lower housing, a microphone disposed in the closed housing, a loud speaker in the container, an amplifier disposed in the intermediately disposed housing, acoustic-insulating and resonance-suppressing means in the closed housing in which the microphone is disposed, acoustic insulating and resonance-suppressing material in the intermediately disposed housing in which the amplifier is disposed, acoustic-insulating and resonance-suppressing material

in the lower housing in which the container is disposed, and acoustic-insulating and resonance suppressing material in the container in which the loud speaker is disposed.

5 7. A group-address system having, in combination, a lectern having a base, a frame supported by the base having side walls and a top wall, a closed housing disposed on the top wall, below which a lower housing is formed, a container in 10 the lower housing, a microphone disposed in the

closed housing, a loudspeaker in the container, acoustic-insulating and resonance-suppressing means in the closed housing in which the microphone is disposed, acoustic-insulating and resonance-suppressing material in the lower housing 5 in which the container is disposed, and acoustic-insulating and resonance-suppressing material in the container in which the loudspeaker is disposed.

EDWARD L. BOWLES. 10
